Primary Examiner — Wan Laymon*(74) Attorney, Agent, or Firm* — Welsh Flaxman & Gitler LLC(57) **CLAIM**

The ornamental design for an incontinence device, as shown and described.

DESCRIPTION

FIG. 1 is a front perspective view of the incontinence device. FIG. 2 is a top view of the incontinence device shown in FIG. 1.

FIG. 3 is a bottom view of the incontinence device shown in FIG. 1.

FIG. 4 is a side view of the incontinence device.

FIG. 5 is an opposite side view of the incontinence device.

FIG. 6 is a rear view of the incontinence device; and,

FIG. 7 is a front view of the incontinence device.
